UNITED STATES PATENT OFFICE.

ROBERT T. JOHNSTON, OF SCOTCH PLAINS, NEW JERSEY, ASSIGNOR TO R. HOE AND CO., OF NEW YORK, N. Y., A CORPORATION OF NEW YORK.

METHOD AND APPARATUS FOR PLATE COOLING AND FINISHING.

1,389,361.

Specification of Letters Patent. Patented Aug. 30, 1921.

Application filed September 6, 1918. Serial No. 252,887.

To all whom it may concern:

Be it known that I, ROBERT T. JOHNSTON, a citizen of the United States, residing at Scotch Plains, county of Union, and State 5 of New Jersey, have invented certain new and useful Improvements in Methods and Apparatus for Plate Cooling and Finishing, fully described and represented in the following specification and the accompanying drawings, forming a part of the same.

This invention relates to certain improvements in method and apparatus for plate cooling and finishing.

It is the especial object of the invention 15 to produce a machine in which a stereotype plate is cooled by contact with a cooling fluid, and then finished after it has been cooled, so that the finishing operation is performed on a plate which has solidified 20 or set to its final form.

A further object of the invention is to provide a machine in which the tail piece formed on the plate during the casting operation is removed while the plate is hot or 25 warm and before the plate is cooled.

It is a further object of the invention to produce a machine in which the plate is rotated in contact with a cooling fluid so that the plate may be cooled by contact with the 30 cooling fluid in a comparatively small space, thus economizing in the size of the machine and economizing in space required for it in the press room and making it convenient and accessible to the operator.

It is a further object of the invention to produce a machine in which a plate may be held in a rotary carrier and subjected to 35 cooling, drying and finishing while rotating in the carrier.

A further object of the invention is to produce a machine in which a plate may be brought into position to be cooled by contact with a cooling fluid and then finished, and in which the plate is automatically fed 40 to the cooling and finishing mechanism and registered in proper position with relation thereto.

A further object of the invention is to produce a machine in which the use of

clutches for starting and stopping the various mechanisms is avoided and in which the mechanisms are driven at a uniform speed, and in which a plurality of plates may be operated on at the same time.

With these and other objects not specifically referred to in view, the invention consists in certain parts and combinations which will be specifically described in the accompanying drawings, in which:

Figure 1 is a side elevation, partly in section and partly broken away, of the machine.

Fig. 2 is a sectional end view showing the driving connections, this section being taken on the line 2-2 of Fig. 1;

Fig. 3 is a plan view, partly in section, of the driving connections, the view being taken on line 3-3 of Fig. 2;

Fig. 4 is a cross sectional detail view on a somewhat enlarged scale, illustrating the plate feeding mechanism, the section being taken on line 4-4 of Fig. 2;

Fig. 5 is a sectional view through the cooling and finishing cylinder, showing the finishing knife and the means for preventing chips from coming in contact with the cooling fluid, the view being taken on line 5-5 of Fig. 1;

Fig. 6 is a horizontal plan view, partly in section, and partly broken away, taken on the line 6-6 of Fig. 5;

Fig. 7 is a vertical longitudinal section taken on the line 7-7 of Fig. 5, partly broken away, of the construction shown in Fig. 6, looking in the direction of arrow A of Fig. 5;

Figs. 8, 9 and 10 are end views, partly in section and partly broken away, showing the finishing cylinder and its operating mechanism and the mechanism for clamping and freeing the plate in various positions, and

Fig. 11 is a cross section of the delivery end of the finishing and cooling cylinder, the section being taken on line 11-11 of Fig. 4.

The machine shown in the drawings includes generally a standard or receiver

on which the hot unfinished plates are deposited by the machine attendant, and cooling and finishing mechanism to which these plates are automatically fed and in which mechanism the plates are clamped in position to have the tail pieces removed, cooled by contact with the cooling fluid, and then finished and delivered from the cooling and finishing mechanism to a suitable delivery. 5 The specific mechanisms by which these various operations are effected may, of course, be widely varied in construction within the scope of the appended claims, but the machine shown is an effective one for 10 performing these functions, and will now be described in detail.

Referring to the drawings, the various parts of the mechanism are supported by suitable frames 1, 2 rising from any suitable 15 support, as bases 3, 4. Supported by the frames 1, 2 are standards 5, 5' which are the receiving and delivery standards respectively. These standards are provided with side ledges 6 on which the straight edges of 20 the plates rest. The receiving standard 5 is formed with a central guide 8 and the receiving standard 5' is formed with a central guide 8'. On these guides reciprocates a feeding mechanism, hereinafter referred 25 to, by which the plates are fed from the receiving stand 5 to the cooling and finishing devices, and from the cooling and finishing devices to the delivery stand 5'.

The cooling and finishing devices as shown 30 are so constructed that the plate is first cooled and then finished in cooled or solid condition. Machines constructed in accordance with the invention will include what may be termed a cooling and finishing cylinder, which is marked generally 9. This cylinder in the particular construction illustrated comprises a rotary shell or carrier 35 supported in suitable bearing frames 10 mounted in standards 12 bolted 40 to, or otherwise secured to the side frame 1 of the machine. This cylinder acts as a carrier to carry the plates so that they may be cooled by contact with the cooling fluid and then finished, this finishing consisting in 45 shaving the inside of the plate out to a predetermined size or thickness. In machines embodying the invention in its preferred form, this cylinder will be capacitated to carry two plates around, one plate being 50 finished while the succeeding plate is moved to contact with the cooling fluid. Means are provided for automatically locking the plates in the shell so that they will be held rigidly in position while being cooled and 55 finished while the succeeding plate is moved to contact with the cooling fluid. Means are provided for automatically locking the plates in the shell so that they will be held rigidly in position while being cooled and 60 finished and unlocking them after finishing so that they may be removed from the cylinder. In the particular construction illustrated for effecting this, the cylinder is provided with a pair of guides or ledges 65 13, 14 (see Figs. 2 and 8 to 10, inclusive)

which extend longitudinally of the finishing cylinder. These ledges form tracks on which the plate is fed into the cylinder and act as abutments for one edge of the plate when the plate is locked in the cylinder. The 70 plate locking means include a pair, one on each side of the cylinder, of locking tongues 15 (see Fig. 4) mounted to slide circumferentially of the cylinder. These locking tongues 15 are carried on slides 17 which 75 have a sliding movement circumferentially of the shell, the slides being held in position by being undercut and working in undercut grooves 16, one of which is shown in Fig. 1, formed in the sides of the cylinder. 80 These tongues project inwardly through slots into the path of one of the straight edges of the plate, one of the ledges being cut away to accommodate the tongue as shown at 15'. These tongues act, when in 85 locked position, to hold the plate firmly against the interior of the shell. While the locking and unlocking sliding movement of the locking plates 20 may be effected in various ways, in the particular construction 90 illustrated the locking plates are normally held in locked position by springs 18, which springs take between suitable abutments 19 on the shell, and projections 20 on the slides. 95

Such holding means is shown only between one set of abutments and projections 20 but it is to be understood that it is provided for both sets.

The means employed for operating these 100 slides to unlock a plate may vary widely. A simple and effective construction for effecting this, however, is illustrated, in which there is provided (see Figs. 8 to 10 inclusive) a striker lever 21 having a striker head 22, this lever being suitably pivoted on a stud 23, mounted in the machine frame. The striker head is recessed as at 24, and in this recess works a striker pin 25 having a beveled end, this striker pin being normally maintained in projected position by a spring 26. The striker lever has at its other end a cam roll 27 which works in a groove of a cam 28 carried on a cam shaft 29, suitably mounted in bearings 30 (see 110 Fig. 3), in the frame of the machine. The parts moving as illustrated by the arrows in Figs. 8 to 10, the projection 20 hits the end of the striker pin 25 and forces the same into the striker head against the spring 26 and as the shell continues its rotation the striker pin immediately springs behind the projection 20. The striker lever is then operated to bear on the outer side of the projection 17 and through it operate the slide 17 against the compression of the spring 18 to release the lock and free the plate, as shown in Fig. 9.

Machines embodying the invention in its preferred form will include constructions 135

whereby the carrier may be stopped after it has made a partial revolution, so that a plate may be subjected to the cooling action while it is rotating with the carrier and, if desired, while the carrier is at rest, so that during the period of rest of the carrier a second plate may be fed to the carrier and a previously cooled and finished plate removed therefrom. The operation of the machine will be continuous, the use of clutches for starting and stopping the carrier being done away with, a continuously running power mechanism being provided, running at a continuous uniform speed, with which the carrier is intermittently engaged automatically. While the construction for effecting this may be varied, in the particular construction illustrated there is provided a shaft 31 suitably mounted (see Fig. 1) in bearings 32 in the supports 12, before referred to. This shaft is continuously driven at a uniform speed through connections hereinafter referred to and is provided at one end with a driving gear 33. The carrier shell is automatically thrown into and out of driving engagement with gear 33 through suitable stop mechanism. While this stop mechanism may be somewhat varied, as illustrated the carrier has fast on one end segment gears 34, 35, gaps 36 being left between the segments. Also fast on the carrier inside the segment gears, are what may be termed starting racks 38. These racks are engaged by a starting pinion 39, which moves the carrier at a predetermined time to bring the segment gears 34, 35 into engagement with the driving gear 33. As illustrated the pinion 39 is operated from a rack 40 mounted to slide on a guide block 41 suitably secured to the frame of the machine. The rack 40 is reciprocated by means of a link 42 attached to the slide at one end and at its other end attached to a rock arm 43 which is pivoted at 44 to a suitable base 45 secured to the machine frame (see Fig. 2). The arm 43 carries a cam roll 46 operating in a groove of a cam 47 on the cam shaft 29 before referred to. With this construction the carrier is automatically brought into driving engagement intermittently and automatically with a continuously running driving gear without the use of clutches and the carrier is driven with uniform movement. The parts are timed so that the carrier is given a partial revolution, then stopped, during which partial revolution and stop the plate is cooled, and then again picked up and again given a partial revolution, during which the plate is finished.

Machines embodying the invention in its best form will include means for feeding the plates into the carrier automatically and registering them in the carrier in correct position without requiring this to be done by the operator, and this means in the preferred construction will also be such that a cooled and finished plate may be removed from the carrier as an unfinished plate is being fed thereto. While this may be effected in various ways, in the machine illustrated (see Fig. 6 and Figs. 8 to 11) the receiving stand 8 beyond the end of the cylinder is provided with a guide frame 48 in which are formed guiding grooves 50 in which slides a reciprocating pawl carrier 51, and the delivery stand 8, hereinafter referred to, is similarly formed. This carrier 51 is recessed, as at 52, and has pivoted in the recess carrier-pawls 53 provided with notched feeding faces 54. These pawls are normally sprung outwardly by springs 55 to feeding position, stops 56, against which the tails of the pawls abut, being provided to limit the movement of the pawls. This pawl carrier reciprocates the length of the machine and when the carrier is reciprocated the first pawl at the left of Fig. 4 passes beyond the rear edge of the plate. On the next reciprocation of the carrier the pawl feeds the plate into the finishing cylinder and, if there has been a cooled and finished plate in the cylinder, the right hand pawl picks up the plate and removes it from the cylinder. With this construction the extent of movement of the plate into the cylinder depends on the movement of the carrier, the plate stopping when the reciprocation of the carrier is stopped. The feeding pawls, therefore, automatically position the plate in the cylinder. Furthermore, it is only necessary for the attendant to place the plate on the feeding stand, no nice positioning of the plate being necessary, the pawls sliding beneath the surface of the plate until free of the ends, when the springs cause them to assume their feeding position. The means for reciprocating the pawl carrier may be varied, but as illustrated include a rack 57 fast to the underside of the carrier. This rack is reciprocated by a gear 58 (see Fig. 1) on a short shaft 59 suitably journaled in the machine. This shaft 59 carries a driving pinion 60 which engages with a rack 61, which slides in vertical sliding frames 62, suitably secured to the base 3 of the machine. This rack is reciprocated by wrist pin 63 on a crank arm 64 from crank 65 driven from power shaft 66 of the machine, hereinafter referred to. The gears 58 and 60 are proportioned to drive the pawl carrier the required distance in each direction at one revolution of the power shaft.

In the best constructions means are provided for cutting the tail piece from the plate and in the best constructions this cutting operation will be effected while the plate is hot or warm and before the plate is acted on by the cooling fluid. While this may be effected in various ways, in the

particular construction illustrated the plate is fed to the finishing cylinder with the tail piece or gate p' foremost. The plate is fed in registered position in the finishing cylinder and clamped therein, as hereinbefore described, and the rotation of the cylinder started. To effect the cutting off of the tail piece, there is provided a rotary cutter 67 mounted on a short shaft 68 suitably journaled in the frame of the machine. 10 This cutter is located just beyond the end of the finishing cylinder on the opposite side from which the plate is fed in and preferably this cutter will be driven at high speed. 15 As illustrated, it is driven directly from power shaft 66 of the machine through a belt 69 over pulleys 70, 71 on the shafts 66 and 68, respectively.

Various means for effecting the cooling 20 of the plate are within the limits of the present invention. In the best construction, however, a cooling bath of water is provided, the water being preferably applied to the interior of the cylinder by 25 spraying or pouring, so as to contact with the back of the plate and cool it, and preferably the plate will be moved past this cooling means by the rotation of the carrier. A concrete embodiment of the cooling devices 30 effecting this is shown in the drawings. As shown, there is provided a main supply pipe 72 (see Figs. 4, 5 and 11) suitably mounted in the frame of the machine, to which water is supplied through a flexible connection 35 72' from any suitable source, not shown. The main supply pipe 72 is provided with a number of branches 73 arranged to distribute water against the rear side of the plate as it is rotated by the carrier and, if 40 desired, during the period in which the carrier is stopped after partial revolution, as hereinbefore described. The water may be supplied continuously during the operation of the machine, or any usual means for 45 turning on or off of the water may be employed.

As the tail piece or gate is cut off as the carrier rotates, and as it approaches the cooling devices, means are preferably provided for preventing the cooling water from wetting the gate piece. As illustrated 50 (see Fig. 11) there is provided an apron 74 secured just within the end of the carrier to the frame 48 before referred to. The branch spray pipes 73 project through 55 this apron and the gate piece is cut from the plate and falls on the outside of this spron and is delivered down an incline 75 (shown in Fig. 2) and delivered from the 60 machine in any suitable or desired manner. The cooling fluid passes through the cylinder and is caught in trough 76 from which it may be removed in any suitable manner, as by pipe 77 (see Fig. 2). After the plate 65 has been cooled by the application thereto

of the cooling fluid as described, the plate is preferably dried before finishing. While the means for effecting this may be varied, as illustrated it comprises perforated air pipes 78, these pipes 78 being supplied with air from any suitable source, not shown, these pipes passing through the carrier and being arranged above the spray pipes 73, so that as the wet plate passes away from the spray pipes it is dried. 75

After the plate has been dried it is finished by shaving out the interior of the plate to the correct diameter. By delaying the shaving operation until after the plate has been cooled and set to its final form, and while it is clamped in the cylinder, a very accurate shaving is effected. The particular means for effecting the shaving of the plate may be varied, but in the particular construction illustrated there is provided a shaving knife 85 79 movably secured, as by a screw bolt 80, to a block 80' secured between the stands 8 and 8' by connecting ribs 80'', as clearly shown in Figs. 4 and 6, the block 80' being broken away in Fig. 4 for the purpose of illustration, but being clearly shown in Figs. 5 and 6, the shell carrying the plate being rotated past this fixed shaving knife. This knife shaves the interior of the plate, bringing it to its proper diameter and thickness. By 90 this shaving operation chips are removed from the plate, and in the best constructions means are provided for removing these chips from the machine so that they will not be wet by the cooling fluid. While the specific 95 means for effecting this may be varied, in the particular construction shown the chips drop into a trough 81 (see Fig. 5) having a bottom 82 and sliding wall 83, which has secured thereto a scraper 83' (see full lines 100 in Fig. 5 and dotted lines in Fig. 7) these sliding parts acting to keep the trough free of chips and to remove the chips from the side of the carrier opposite to that in which the plate entered. The movable bottom may 105 be reciprocated in any suitable manner. For simplicity of construction, the pawl carrier 51, before referred to, is utilized for this purpose. As shown, (see Figs. 5 and 7) the bottom of the pawl carrier has secured thereto a stop 84, which stop, during the reciprocation of the carrier, contacts with a projection 85 on wall 83 before referred to, the slide being moved forward by the pawl carrier against a spring 86, the extent of 110 its movement being the extent of the movement of the pawl carrier, which is as shown to a point beyond the outer end of the cylinder, which returns it to position after it has removed the chips from the trough, the 115 chips, as they are removed from the carrier, falling down the incline 75, before referred to.

The driving mechanism for operating the various parts of the machine may be some- 120

what varied, but these means will be such that they will be automatic in operation and drive the various parts without the use of clutches. As shown, referring to Figs. 1 and 3, the machine is driven by the main power shaft 66, before referred to, from a source of power, such as electric motor 87, the power shaft 66 being connected with the motor by a suitable coupling 88. This power shaft has secured thereto a worm 89 which meshes with a worm wheel 90 on a transverse shaft 91 suitably journaled in bearings 92 in the machine frame. The shaft 92 has secured at one end a bevel gear 93 which meshes with the bevel gear 94 on an oblique shaft 95, suitably journaled in bearings 96, this oblique shaft at its other end carrying a miter gear 97 meshing with a miter gear 98 on the end of the shaft 31, before referred to, by which the finishing cylinder is driven, this construction providing a continuous driving mechanism for the finishing cylinder.

The shaft 91 toward its other end carries a worm 99 which meshes with a worm wheel 100 on the cam shaft 29, before referred to, thus driving the cam shaft through which the starting and stopping movements of the finishing means are effected and the plate locking devices operated for locking and freeing the plate in the cylinder.

The plates as removed from the finishing cylinder may be disposed of in any suitable manner, as to a delivery stand 102, from which they may be removed by hand or in any other desired manner.

The operation of the machine may be briefly described as follows:

The motor is started and the machine put in operation; a cast plate with the tail piece p' is then placed by the operator on the receiving stand 5, with the tail piece extending forwardly. The pawl carrier begins its reciprocating movement and the first pawl 53 moves to the extreme left of the stand (looking at Fig. 1) passing under the plate. As soon as it passes beyond the plate the pawl springs up into feeding position and feeds the plate forward into the finishing cylinder the required distance as the carrier again reciprocates, where it stops, leaving the plate in registered position. One of the plate locking slides is brought by the rotation of the carrier into position to be operated on by the striker lever 21, which moves the slide against spring 18 to bring the locking tongue below the edge of the plate as the plate moves into the cylinder, the spring then moving the slide into position to lock the plate in the cylinder. The carrier is then started by pinion 39 which rotates the carrier sufficiently to bring one of the gears 34, 35 into mesh with the driving gear 33, and gives the carrier a partial rotation past the cooling pipes or nozzles 73 and then is

stopped. During this movement the pawl carrier has made a return movement and during the stop of the cylinder has positioned a second plate therein, which is locked through the plate locking devices. The rotation of the carrier is then resumed and the first plate is dried by the drying pipe 78 and is then finished by the finishing knife or shaver 79. After the plate has been finished and the carrier given a full revolution, it is again stopped and the cooled and finished plate unlocked. The steps by which this is effected are shown in Figs. 8, 9 and 10 of the drawings. In Fig. 8 the carrier is shown as having completed almost a half revolution, the carrier driving gear 35 being shown as just about to go out of mesh with the driving gear 33, and the pinion 39 is engaging with the starting rack 38 which moves the carrier to complete the half revolution and brings the parts to the position shown in Fig. 9. As there shown the pinion 39 is no longer operated as the cam roll 46 is on the idle part of the cam 47, and the carrier comes to rest, the cam being timed to allow a period of rest sufficiently long to permit the removal of a finished plate and the insertion of an unfinished one. As the carrier comes to rest the cam roll 27 has run up on the high part of the cam 28 and operates the striker 25 to move the slide 17 to the left (in Fig. 9) through the projection 20 thereby releasing the top plate, which is shown in that figure as unlocked. The cam 47 continuing its movement again operates the cam roll 46 to move the rack 40 which movement through the pinion 39 and the starting rack 38 moves the carrier sufficiently to bring the other carrier gear 34 into mesh with the driving pinion 33, which position is shown in Fig. 10. It will, of course, be understood that the released plate is removed from the carrier and a finished plate inserted therein, while the parts are in the position shown in Fig. 9, and the locking slide is in its unlocked position. At this time the pawl carrier is making its third forward movement and during this movement removes the finished plate from the finishing cylinder and brings a third plate into position thereon, the finished plate being moved out onto the delivery stand 8'.

It will be observed that while the cooling bath, finishing mechanism and drying means act in that order, in the first instance, upon a plate, they also thereafter act simultaneously on the plate when the latter reaches the drying means and continue to so act until the plate gets beyond the cooling bath.

A machine as shown and described above has been produced which is continuous and automatic in operation and by which a plate is very accurately finished.

While the described means shown for carrying out the operations are simple and

effective, it will be understood that a considerable variance may be made in their specific constructions without departing from the invention, and it is understood that such changes and variations may be made without departing from the invention as described in the claims annexed hereto.

What is claimed is:

1. The combination of a cooling bath and a finishing mechanism arranged to act in that order on a plate, and means for effecting the relative movement of a plate and said elements for such action.
2. The combination of a cooling bath, drying means and a finishing mechanism arranged to act in that order on a plate, and means for effecting the relative movement of a plate and said elements for such action.
3. The combination of a tail-severing mechanism, a cooling bath and a finishing mechanism arranged to act in that order on a plate, and means for effecting the relative movement of a plate and said elements for such action.
4. The combination of a tail-severing mechanism, a cooling bath, drying means and a finishing mechanism arranged to act in that order on a plate, and means for effecting the relative movement of a plate and said elements for such action.
5. The combination of means for applying a cooling fluid to the plate, and means for then finishing the cooled plate.
6. The combination of a supply of cooling fluid, means for moving the plate by the fluid supply to be cooled, means for stopping the plate while being acted on by the cooling means, and means for thereafter finishing the cooled plate.
7. The combination of means for applying a cooling fluid to a plate, means for moving a plate into position to be acted on by the cooling means, plate finishing means, said moving means being capacitated to move a second plate into position to be acted on by the cooling means while the first plate is being finished after being cooled.
8. The combination of means for applying a cooling fluid to a plate, means for feeding a plate into position to be cooled thereby, means for finishing the cooled plate, said feeding means being capacitated to feed a second plate into position to be cooled and to remove the cooled and finished plate.
9. The combination of a supply of cooling fluid, means for rigidly holding a plate, means for positioning a plate so that it is cooled by contact with the cooling fluid, and means for thereafter finishing the cooled plate while it is rigidly held.
10. The combination of a rotary carrier, of means for feeding a plate thereto, plate cooling means to which the plate is moved by the carrier, plate finishing means arranged to finish the plate after it has been

cooled, said feeding means being capacitated to feed a second plate to the carrier, and means for removing the cooled and finished plate from the carrier while the second plate is being fed thereto.

70

11. The combination of a rotary carrier, means for feeding a plate thereto, means for clamping the plate to the carrier, plate cooling means and plate finishing means adjacent the carrier past which the plate is moved and by which it is finished after it is cooled, and means for delivering the plate from the carrier.

75

12. The combination of a rotary carrier, plate cooling means located adjacent thereto, means for feeding a plate to the carrier, means for rotating the carrier to move the plate past the plate cooling means, means for stopping the carrier, said feeding means being capacitated to feed a second plate to the carrier while the carrier is stopped, means for finishing the first plate after it has been cooled, and means for delivering the finished plate from the carrier.

80

13. The combination of a rotary carrier, means for feeding a plate to the carrier and for clamping it in registered position therein, means in the carrier for applying cooling fluid to the back of the clamped plate as the carrier rotates, means for finishing the plate after it has been cooled, and means for removing the finished plate from the carrier.

85

14. The combination of a rotary carrier, stationary plate cooling devices and plate finishing devices past which the carrier successively moves in the order stated, means for feeding a plate into the carrier, means for clamping the plate therein, means for freeing the plate after it is finished, and means for delivering the finished plate from the carrier.

90

15. The combination of a rotary carrier, means for feeding a plate thereto, plate cooling means to which the plate is moved by the carrier, plate drying means, plate finishing means arranged to finish the plate after it has been cooled, and means for removing the plate from the carrier after it has been cooled and finished.

95

16. The combination of a rotary carrier, means for feeding a plate thereto, plate cooling means to which the plate is moved by the carrier, plate drying means, plate finishing means arranged to finish the plate after it has been cooled and dried, said feeding means being capacitated to feed a second plate to the carrier, and means for removing the cooled and finished plate from the carrier while the second plate is being fed thereto.

100

17. The combination of a rotary carrier, means for feeding a plate thereto, means for registering the plate on the carrier, plate cooling means to which the plate is moved by the carrier, plate finishing means ar-

125

130

ranged to finish the plate after it has been cooled, and means for removing the cooled and finished plate.

18. The combination of means for cool-

5 ing a plate by contact with a cooling fluid, means for thereafter finishing the plate, and means whereby the plate is fed to the cooling and finishing means in registered position.

10 19. The combination of means for applying a cooling fluid to a plate, means for drying the plate, and means for then finishing the cooled and dried plate.

15 20. The combination of plate finishing means, plate drying means, plate cooling means, and means for rotating a plate past the finishing, cooling and drying means.

21. The combination of a rotary carrier, plate finishing means, plate cooling means, 20 and plate drying means, all located adjacent the carrier and past which a plate is rotated.

22. The combination of a rotary shell, 25 means for clamping a plate in the shell, plate finishing means, plate cooling means, and plate drying means located within the shell past which the plate is rotated by the shell.

23. The combination of a rotary carrier, 30 a supply of cooling fluid for cooling the plate on the carrier into contact with which fluid the carrier moves the plate, means for delivering the plate from the carrier, and means for feeding a second plate to the carrier before the first plate has been removed.

35 24. The combination with a rotary carrier, of a supply of cooling fluid for cooling the plate as it rotates on the carrier, means for stopping the carrier after a partial revolution, means for feeding a plate 40 to the carrier while it is stopped, and means for removing a cooled plate from the carrier.

25. The combination of a rotary carrier 45 capacitated to carry two plates around, means for feeding the plates to the carrier, a supply of cooling fluid into contact with which the carrier moves the plates, means for stopping the carrier after a partial revolution, means for feeding a second plate to the carrier while the carrier is stopped, 50 means for again starting the carrier, and means for delivering the cooled plate therefrom.

26. The combination of means for cooling 55 a plate by contact with a cooling fluid, means for finishing the plate, and means for preventing the chips or shavings from the plate from being wet by the cooling fluid.

27. The combination with a rotary shell, 60 of finishing and cooling means located within the shell past which the plate is moved by the shell, and means for preventing chips or shavings from the plate from being wet by the cooling means.

28. The combination of a receiving stand, 65 a rotary finishing and cooling cylinder, and

a feeding mechanism for feeding a plate from the receiving stand into the cylinder in registered position therein.

29. The combination of a receiving stand, 70 a rotary finishing and cooling cylinder, and a feeding mechanism for feeding a plate from the stand into the cylinder and removing a finished plate therefrom.

30. The combination of a receiving stand, 75 a finishing and cooling cylinder, a reciprocating feeding bar, feeding devices carried by the bar for feeding a plate from the stand into the cylinder and removing a finished plate therefrom.

31. The combination of a receiving stand, 80 a finishing and cooling cylinder, and a reciprocating feeding bar provided with spring pressed pawls for feeding a plate into the cylinder and removing a finished plate therefrom.

32. The combination of a finishing cylinder, 85 a continuously running driver therefor, segmental driving gears on the cylinder each of which gives the cylinder almost a half rotation, and means for giving the cylinder a movement to complete a half rotation and then stop the cylinder.

33. The combination of a finishing cylinder, 95 a continuously running driver therefor, segmental driving gears on the cylinder each of which gives the cylinder almost a half rotation, means for giving the cylinder a movement to complete a half rotation and then stop the cylinder, locking devices for locking and releasing a plate, and means for actuating the locking devices after the carrier has thus completed a full half revolution.

34. The combination with a finishing cylinder, 100 of a continuously running driver, segment gears on the cylinder, starting racks on the cylinder, and means for engaging the starting racks to move the cylinder and bring the gears in engagement with the driver.

35. The combination of a finishing cylinder, 105 a continuously running driver therefor, segmental driving gears on the cylinder, starting racks on the cylinder, a starting pinion, and cam operated means for causing the pinion to engage the racks and bring the gears in engagement with the driver.

36. The combination of a finishing cylinder, 110 stationary ridges on the cylinder on which the straight edges of the plates rest, movable tongues for lifting the plates along the ridges and locking them in the cylinder, slides on which the tongues are carried, and means for operating the slides circumferentially of the cylinder.

37. The combination with a finishing and 115 cooling cylinder, of means for cooling a plate in the cylinder by contact therewith of a cooling fluid, means for finishing the plate after it has cooled, means for preventing the

chips from coming into contact with the cooling fluid, and means for renewing the chips.

38. The combination with a cooling and 5 finishing cylinder, of means for wetting a plate in the cylinder to cool the plate, means for finishing the cooled plate, a trough into which the chips are directed from the finisher, and means for removing 10 the chips from the trough.

39. The combination of a continuously 15 running driver, a cutter for removing the tail piece from the plate, a shaft therefor, driven at the shaft speed of the driver, a finishing mechanism, continuously driven operating means for driving the finishing mechanism from the driver at a lower shaft speed, means for stopping the finishing mechanism after a partial movement there- 20 of, and means operated from the driver for automatically starting the finishing mecha- nism after it has been stopped.

40. The combination of a cooling bath 25 and a finishing mechanism arranged to act in that order on a plate, and a rotary car- rier for moving a plate past the same.

41. The combination of a cooling bath, 30 drying means, and a finishing mechanism arranged to act in that order on a plate, and a rotary carrier for moving a plate past the same.

42. The combination of a tail-severing 35 mechanism, a cooling bath, and a finishing mechanism arranged to act in that order on a plate, and a rotary carrier for moving a plate past the same.

43. The combination of a tail-severing 40 mechanism, a cooling bath, drying means, and a finishing mechanism arranged to act in that order on a plate, and a rotary car- rier for moving a plate past the same.

44. The combination of a cooling bath 45 and a finishing mechanism arranged to act in that order on a plate, a carrier rotating past the same and adapted to carry a plurality of plates one behind another, means for intermittently rotating said carrier with one plate in cooling and another in discharging position when the carrier is at rest, and 50 means for discharging the latter plate from and introducing an unfinished plate into the carrier while the carrier is at rest.

45. The combination of a cooling bath, 55 drying means, and a finishing mechanism ar- ranged to act in that order on a plate, a carrier rotating past the same and adapted to carry a plurality of plates one behind another, means for intermittently rotating said carrier with one plate in cooling and another in discharging position when the carrier is at rest, and means for discharging the latter plate from and introducing an unfinished plate into the carrier while the carrier is at rest.

46. The combination of a tail-severing

mechanism, a cooling bath and a finishing mechanism arranged to act in that order on a plate, a carrier rotating past the same and adapted to carry a plurality of plates one behind another, means for intermittently 70 rotating said carrier with one plate in cooling and another in discharging position when the carrier is at rest, and means for discharging the latter plate from and introducing an unfinished plate into the carrier 75 while the carrier is at rest.

47. The combination of a tail-severing 80 mechanism, a cooling bath, drying means, and a finishing mechanism arranged to act in that order on a plate, a carrier rotating past the same and adapted to carry a plurality of plates one behind another, means for intermittently 85 rotating said carrier with one plate in cooling and another in discharging position when the carrier is at rest, and means for discharging the latter plate from and introducing an unfinished plate into the carrier while the carrier is at rest.

48. The combination of plate finishing 90 means, a carrier rotating past the same and adapted to carry a plurality of plates one behind another, means for intermittently rotating said carrier, and means for dis- 95 charging a finished plate from and introducing an unfinished plate into the carrier while the latter is at rest.

49. The combination of plate finishing 100 and cooling means, a carrier rotating past the same and adapted to carry a plurality of plates one behind another, means for 100 intermittently rotating said carrier, and means for discharging a finished plate from and introducing an unfinished plate into the carrier while the latter is at rest.

50. The combination of plate finishing, 105 cooling and drying means, a carrier rotat- ing past the same and adapted to carry a plurality of plates one behind another, means for intermittently rotating said car- 110 rier, and means for discharging a finished plate from and introducing an unfinished plate into the carrier while the latter is at rest.

51. The combination of tail-severing, 115 plate finishing, cooling and drying means, a carrier rotating past the same and adapted to carry a plurality of plates one behind another, means for intermittently rotating said carrier, and means for discharging a 120 finished plate from and introducing an un- finished plate into the carrier while the lat- ter is at rest.

52. The combination of a cooling bath, 125 a carrier rotating past the same and adapted to carry a plurality of plates one behind another, means for intermittently rotating said carrier to bring one plate in cooling and another in discharging position when the carrier is at rest, and means for dis- 130 charging the latter plate from and intro-

ducing another plate into the carrier while the latter is at rest.

53. The combination of a cooling bath, finishing mechanism and drying means arranged to act simultaneously upon a plate, and means for effecting the relative movement of a plate and said elements.

54. The combination of a cooling bath, finishing mechanism and drying means arranged to act first successively and thereafter simultaneously upon a plate, and means for effecting the relative movement of a plate and said elements.

55. The combination of a cooling bath, finishing mechanism and drying means arranged to act first in that order and thereafter simultaneously upon a plate, and means for effecting the relative movement of a plate and said elements.

20 56. The method of finishing stereotype

plates consisting in first cooling the plate by contact with a cooling fluid and then finishing the same.

57. The method of finishing stereotype plates which consists in first cooling the 25 plate by contact with a cooling fluid, drying it, and then finishing the same.

58. The method of finishing stereotype plates consisting in first severing the tail of the plate while hot, then cooling the plate 30 by contact with a cooling fluid, drying it, and then finishing the same.

59. The method of finishing stereotype plates consisting in first severing the tail of the plate while hot, then cooling the plate 35 by contact with a cooling fluid, and then finishing the same.

In testimony whereof, I have hereunto set my hand.

ROBERT T. JOHNSTON.
